M. J. SMITH.

COMBINED WINDOW SHADE AND SHUTTER.

APPLICATION FILED NOV. 20, 1913.

1,095,292.

Patented May 5, 1914.

UNITED STATES PATENT OFFICE.

MARTIN JAMES SMITH, OF BROCKTON, MASSACHUSETTS.

COMBINED WINDOW SHADE AND SHUTTER.

1,095,292.

Specification of Letters Patent. Patented May 5, 1914.

Application filed November 20, 1913. Serial No. 802,079.

To all whom it may concern:

Be it known that I, MARTIN J. SMITH, residing at Brockton, in the county of Plymouth and State of Massachusetts, have 5 invented a new and Improved Combined Window Shade and Shutter, of which the following is a specification.

This invention has for its purpose to provide an improved construction of window shade device, in which the several parts are so designed and co-operatively connected whereby the same, under one adjustment, serves as an ordinary window shade, and under another adjustment is adapted 15 for forming a substantially solid closure member which, when the blades thereof are of metal, serves as a fire-proof shutter.

My invention also embodies a combined blind and shutter construction, in which the 20 blades are arranged vertically and adapted for being drawn together like a bellows, an improved co-operative arrangement of supporting means on the window frame or casing including sub-frames upon which the 25 entire shutter and blind mechanisms are mounted, and other means for holding the several blades relatively uniformly spaced apart, and still further means for actuating the several blades for moving them while 30 held projected to their open position, to thereby cause them to fold upon each other and to one side of the window casing; other devices mounted upon the window frame being also provided for swinging the 35 several blades to close upon and lap each other to thereby provide, as it were, a solid shutter body, adapted for being held locked to its said closed position.

In its more complete nature, my invention 40 consists of a combined shade and shutter means that embodies the peculiar construction and novel arrangement of the parts hereinafter fully explained, specifically pointed out in the appended claims, 45 and illustrated in the accompanying drawing, in which:

Figure 1 is a perspective view of a window equipped with my improved combined shade and shutter, the shade and shutter devices for the upper sash being shown adjusted as a fire-proof shutter, and the like devices for the lower sash being shown adjusted as a shade, the vanes of blades being 50 at their most widely separated positions. 55 Fig. 2 is a front elevation of a portion of

the window frame with my improvements applied, the several blades or vanes being shown as drawn back to a "closed up" position. Fig. 3 is a perspective view of the upper ends of one set of vanes or blades, 60 the supporting rod therefor, the rod holders and the flexible or chain connections that join the front and the back edges of the said upper ends of the vanes. Fig. 4 is a perspective view of one of the vanes, with 65 the guide rings at the upper and lower ends thereof. Fig. 5 is a detail sectional view of one of the guide rings and its hinged connection with the blade or vane. Fig. 6 is a detail perspective view of one of the rod 70 holders, the gravity drop or latch member thereof being at its rod holding position. Fig. 7 is a similar view, the said latch member being shown swung up to release the rod. 75

In the drawing, I have shown a window frame with an upper and a lower sash, and each sash equipped with my improved combined shade and shutter attachment.

The same numerals indicate like parts in 80 the upper and lower attachments and since the construction of the said two attachments and the manner of operating the same are alike, I shall describe but one of the said attachments in detail. 85

In carrying out my invention, my combined shutter and window shade comprises a series of vertically disposed blades or vanes 1, and they are connected with each other by small chains 20, at the top and the bottom, and at the front and rear edges thereof, and the said leaves are of such width and are spaced apart from each other a distance slightly less than the width of the blades, to thereby allow the several leaves 90 or blades to lap upon each other when they are turned to their flatwise position, (see Fig. 1) to thereby form as it were, a solid body for serving as a fire shutter, when the blades are made of metal. 95

Each blade or leaf 1, at the top and bottom of its back edge, carries a ring 2 and the said rings are hingedly connected to the said blades and in such a manner that the blades or leaves 1 may be readily swung 100 laterally to close upon each other.

In the practical application of my invention, I have provided for readily applying a full set of shutter or blind blades upon the window frame and for conveniently re- 110

moving the same, as desired, and to that end, I use two cross rods or bars 3, one of such rods forming a hanger and guide for the lower ends of the blades or leaves 1, 5 and the other, a hanger and guide for the upper ends of the said blades, since the upper and lower rings 2-2 are loosely held on their respective guide and supporting rods, in the manner best shown in Fig. 5.

10 For quickly attaching to, or removing the rods from the window casing, I have provided the supporting device shown in detail in Figs. 6 and 7, one of such devices being employed for each end of the hanger or 15 guide rods 3. The said supporting device comprises a hanger bearing 4, the upper and lower ends of which are apertured as at 40 for receiving the attaching screws 41 while the body portion proper 42, is bent 20 outwardly to a substantially J-shape, to thereby project the hanger portion 43, proper, inwardly and away from the window frame or casing when the said bearing 4 is applied for use. The hanger portion 25 43 of the member 4 has a vertically elongated slot 45 that opens through the lower end 46 of the hanger 4.

By referring now more particularly to Figs. 6 and 7, it will be seen that each device 30 4 includes a hanger hook 5 that is pivotally suspended over the outer face of the bracket or hanger portions 43. Hook 5, the general shape of which is best shown in Figs. 6 and 7, is pivotally supported at a point directly above the slot 45 in the hanger 4 and the weight of the body thereof is so distributed that the said hook normally swings 35 downwardly by its own gravity, so that its front or claw-like end 55 passes over the slot 45 (see Fig. 6). The upper and lower edges of the claw-like end 55 of the hook 5 are curved eccentrically to the pivot of the hook, the reason for which will presently appear and the curvature of the said under 40 edge of the hook and the heel or weighted portion 50, are relatively such that to release the hook from the bar it is only necessary to press against the said heel end 50 in the direction indicated in Fig. 7, to cause it to 45 swing outwardly away from under the bar from the hanger bracket.

By reason of forming the hangers 4 in the manner shown and described, and making the rods 3 of a length slightly greater than 50 the distance between each opposing pair of the said devices, it is apparent, from Figs. 6 and 7 of the drawings, that in applying my improved combined shutter and blind appliance, it is only necessary to press the 55 ends of the cross rods 3 up against the hooks 5, which, under such pressure, swing out to uncover the entrance of the slots in the brackets 4, it being also clear that so soon as the ends of the rods pass up over the claw 60 end of the hooks, the latter return to their

normal position by gravity, close off the slots and form hangers on which the rods are then supported.

The peculiar construction of the hanger allows a rod to slide into the slot from the bottom of the hanger upward and when pivoted in place the swinging or gravity hook 5 drops in place and thereby holds the rod in such position that it resists pressure on all sides and so closed upon that it cannot 70 bounce or jump out when pushed in any direction.

6 designates a pull cord or cable that hangs pendent on the window casing, passes through guide eyes 60, and then passes 75 through all of the upper rings 2, and is made fast to the outermost one of the leaves or blades 1. By pulling on the cord 6, the outermost one of the leaves or blades is first pulled to slide inwardly on the guide 80 rods 3 until it engages the next leaf or blade gathers against the said blade and additional ones or all of the other blades when it is desired to fold up the leaves or blades to give 85 full clearance to the window, as shown in 90 Fig. 2, it being obvious that since the blades or leaves are flexibly connected at the upper and lower edges the said leaves successively fold up against or are pulled out from each other. 7 designates another pull cord at the 95 other side of the window that is so guided and connected with the outer leaf of the set of leaves or blades, so that in pulling on the said cord 7, the leaves are drawn out to their opened position.

For swinging the blades on their pivots to partly or wholly close over each other, pull cords 8 are located at each side of the window frame that are guided in the eyes 80 on the window casing and join, by hook and eye connections with the outer edge of the outermost and innermost ones of the blades, as shown, it being apparent that by using the two side cords 8, the leaves can be 100 swung laterally on their pivots, in either direction desired.

By reason of bodily supporting the blades or leaves upon an upper and a lower cross rod in the manner shown and described, and providing upper and lower supports having 105 automatically adjustable hanger hooks that operate as stated, the entire leaf or blade holding structure can be bodily and quickly placed in operative position, as the operator in applying the said structure by lifting the 110 upper cross bar up into position in the upper hanger devices can so hold the said structure that the lower cross rod simultaneously 115 engages and moves into the hanging position onto the lower hanger device.

By reason of curving the upper or bearing edge of the claw-like end 55 of the hook eccentrically with respect to the pivot of the said hook, as before stated, while the hook 120 is held to its slot closing position by its own 125

gravity, it cannot, under normal conditions, move from its swung down or closing position until it is forcibly pushed backward by the pressure on the heel end thereof (see 5 Fig. 7) it being obvious that when pressure is thus applied to the hook, the inside bearing curvature of the hook will cause the bar to rise up in the slot, the said inside curvature being also such that the bar when 10 it is supported by the hook seats thereon in such a manner that it keeps the said hook to its spring or slot closing position.

What I claim is:

1. In a window shade, upper and lower 15 supporting brackets each including a member having an opening from beneath, of upper and lower slat supporting bars adapted to be bodily moved up into slots of said members and gravity dropped latch devices 20 for automatically closing said slots and forming rest bearings for said rods and slats mounted on said supporting bars.

2. In a window shade, the combination with the upper and lower transverse slat 25 bars, of bar holding fixtures each comprising a member having a rod receiving slot opening from beneath, and a gravity actuated pivoted hook member adapted to drop beneath said rods to close said openings and 30 form bearings for supporting said rods, said hook members being held to their slot closing position by its own gravity.

3. In a window shade, the combination with the upper and lower transverse slat 35 bars, of bar holding fixtures each comprising a member having a rod receiving slot opening from beneath, and a gravity actuated pivoted hook member adapted to drop beneath said rods to close said openings and 40 form bearings for supporting said rods, said hook members being held to their slot closing position by its own gravity, the upper and lower edges of the said hook being formed eccentrically with respect to the 45 pivot of the hook.

4. In a window shade, the combination with the upper and lower supporting rods, of slat members, rings mounted on said upper and lower rods, one on each rod for each slat member, pivotal connections between 50 said slat members and their respective rings, pull cords for moving said slat members bodily along said rods, and flexible members connected with said slat members for moving them on their pivots to open 55 or close the window opening.

5. In a window shade, upper and lower supporting bars, slats, a ring for each slat on each bar, a pivotal connection between the respective slats and their respective 60 rings, a pull cord passing through said rings and connected to one of said slats, said pull cord having its ends pendent at the sides of the window whereby all of said slats may be bodily moved along said rods 65 to one side of the window frame, and flexible connections between the edges of said slats for spacing them apart, and means by which said slats may be moved on their pivot with the rings for opening or clos- 70 ing the window opening.

6. In combination with a shade supporting cross bar, of bar holding fixtures each comprising a member having a bar receiving slot opening from beneath, and a gravity 75 actuated hook member adapted to drop beneath the bar when the latter is pushed up past the said hook, the said hook member having its upper and lower bar engaging edges formed eccentrically to its pivot 80 whereby when the said bar is held within the slotted member, the said bar engages and holds the hook from swinging back and when the bar is pushed upwardly against the said hook it swings the said hook back 85 to uncover the slot.

MARTIN JAMES SMITH.
